12 Claims. (Cl. 120—96)

1

My present invention relates to a pencil sharpener.

One of the objects of my present invention is to provide a pencil sharpener having a means for simultaneously gripping and feeding the pencil into the machine.

Another object of my present invention is to provide an electric motor to drive the pencil sharpener having a slip clutch connected thereto so as to prevent the breakage of any parts of the apparatus.

An additional object of my invention is to mount the gripping and feeding means on a plurality of symmetrically arranged guiding elements located near a spiral gear which actuates the gripping and feeding means.

The novel features which I consider as characteristic for my invention are set forth in particular in the appended claims. The invention itself, however, both as to its construction and its method of operation, together with additional objects and advantages, will be best understood from the following description of specific embodiments when read in connection with the accompanying drawings, in which:

Fig. 1 is a partial cross section of a view of a pencil sharpening machine according to the invention taken from the side on which the pencil enters the machine and as viewed in the direction of arrow C of Fig. 2;

Fig. 2 is a cross section taken on the line A—B of Fig. 1, and looking in the direction of the arrows;

Fig. 3 is a cross section taken on the line D—E of Fig. 1, and looking in the direction of the arrows;

Fig. 4 is a view of the gripping elements as viewed in the direction of arrow F of Fig. 2;

Fig. 5 is a view of a flat spiral gear as viewed in the direction of arrow F of Fig. 2;

Fig. 6 is a view of a feeding gear shown on an enlarged scale;

Fig. 7 is a sectional view of a control lever for stopping the operation of the apparatus;

Fig. 8 is a view of the stopping apparatus of Fig. 7, as seen in the direction of arrow G of Fig. 7;

Fig. 9 is a sectional view taken along the line H—J of Fig. 7, and looking in the direction of the arrows;

Fig. 10 is a part of a machine stopping apparatus as viewed in the direction of arrow K in Fig. 11;

Fig. 11 is a plan view of the machine stopping apparatus shown in Fig. 10;

2

Fig. 12 is a partial sectional view of the motor and a slip clutch connected thereto;

Fig. 13 is a plan view of a two bladed knife;

Fig. 14 is an elevational view of the knife shown in Fig. 13;

Fig. 15 is an elevational view of another type of knife;

Fig. 16 shows a pencil point obtained by means of the knife shown in Figs. 13 and 14;

Fig. 17 is a sectional view of an elastic sealing member to protect the gearing of the machine from shavings;

Fig. 18 is a sectional view of another form of sealing means taken along the line L—M of Fig. 19; and

Fig. 19 is a sectional view taken along the line N—O of Fig. 18, and looking in the direction of the arrows.

The pencil sharpening machine of my present invention comprises a frame 1 which has formed integrally therewith a circular rim 2 having a disc 3 fastened thereto, the disc 3 having a central conical opening 4 which is aligned with a corresponding opening 5 located in the frame 1 opposite to said opening 4. The opening 5 has a conical extension 6 integral therewith formed so as to correspond to a point of a pencil to be sharpened, whereby the pencil is properly supported within the machine.

Centrally arranged with respect to opening 4 and on the inner surface of the disc 3 is located a disc shaped boss which is provided on its surface, which is parallel to the inner surface of disc 3, with spiral gear teeth cut therein, as shown in Fig. 5. A guiding plate 8 is freely and rotatably mounted about the shoulder of spiral gear 7. The said plate 8 has located therethrough guide slots 60 which have an arcuate shape and are arranged at a distance from the center of plate 8, as shown in Fig. 1. In spaced relation to the vertical inner surface of plate 8 is located a gear wheel 10 which is rotatably mounted and is aligned with plate 8. The gear wheel 10 is provided with gear teeth 11 which mesh with a pinion 12 which is connected by means of shaft 13 to a worm drive 14 which is operatively connected to drive shaft 15, which drives the sharpening tool 16. The gearing by which gear wheel 10 is connected to drive shaft 15 provides a reduction in the speed of gear wheel 10 as compared to the rotative speed of shaft 15 whereby the elements which grip the pencil, as will be explained below, rotate the pencil much slower than the shaft 15 is rotated. The gear wheel 10 has a flat flange 17 having a surface located ad-

ja cent to but spaced from plate 3 and parallel thereto. The flange 17 has three openings provided therein in which are pivotally mounted the pins 18.

In the space between plate 8 and flange 17 are located the guiding segments or elements 19, arranged as shown in Fig. 4, and to which the above mentioned pins 18 are fixed. Also joined to the guiding elements 19 are additional pins 9 which actuate the guiding elements 19. The elements 19 carry bearings 20 on each of which is located a feeding gear 21, shown in Fig. 6, whose teeth are preferably so formed that they have a sharp angular flat surface 22 extending in the feeding direction and only have an involute configuration on the other side of the tooth from said angular surface 22. As a result of the point shape of the teeth 22 the pencil can be effectively held so that it does not slip in the holding apparatus and will not be pushed out of the machine as a result of the cutting pressure of the cutting tool 16. The teeth of the feeding gears 21 mesh with the ways between the teeth of spiral gear 7. As a result of this construction the pencil is more firmly held as the cutting pressure becomes greater in an axial direction of the pencil because the pressure on the teeth 22 is transmitted in a radial direction upon the spiral gear teeth of spiral gear 7. The three guiding elements 19 are held together by spring means, such as for example, the coil spring 23 or any conventional spring means, so that the guiding elements 19 are urged in their idle position towards the central axis about which they are arranged.

As may be seen from Fig. 3, ring 24 which is integral with plate 8 is engaged by a gripping means 25 which is provided with a slot. The said gripping means 25 is integral with a guiding lever 26 which carries at its outer free end an element 27 located at right angles thereto. The guiding lever 26 bears with its other free end against a stop 28 which is fixed to the frame 1.

Rotatably and coaxially mounted with respect to plate 8 and gear wheel 10 is a ring-shaped disc 29. This disc 29 for reasons of clarity is not shown in Fig. 2 but may be seen in Figs. 1 and 3. As may be seen from Fig. 3, the disc 29 is rotatably mounted about hollow element 30 formed integrally with the housing 1. The ring-shaped disc 29 carries at an end thereof an operating lever 31 by means of which the disc 29 may be rotated about element 30 through a certain angle. The operating lever 31 carries on a pivot pin 32 a pawl 33 which is provided at its upper free end 34 with an inclined surface, which is adapted to bear against a corresponding surface on a stop 35 mounted on the housing 1. The pawl 33 is urged outwardly by means of a leaf spring 36, or the like, against a stop (not shown). In the position shown in Fig. 1 the pawl 33 is engaged at its upper part with the guiding lever 26, 27, the said guiding lever 26, 27 being urged upwardly by means of a spring 36.

According to a special form of the invention which is illustrated in Figs. 7 to 10, the machine comprises an automatic stopping mechanism which is released by the point of the pencil being sharpened. The stopping mechanism comprises a stop pin 37 which, as may be seen in Fig. 9, is cut away at its lower portion and which is slidably mounted in sleeve 38 where it bears against spring 39. To the central portion of stop pin 37 is pivotally connected the control lever 40. This control lever 40 is bifurcated at one end thereof, the said bifurcated end engaging an ex-

tension 42 about which said control lever is adapted to pivot, the said extension 42 being eccentrically mounted with respect to the rotatably mounted pin 44 which has an element 43 rigidly attached thereto by means of which the position of pin 44 and eccentric extension 42 may be adjusted.

At the lower end of stop pin 37 is located switch operating member 45 which is pivotally mounted on pin 46. The switch operating element 45 carries at its free end an arcuate shaped element 47 which has a curved surface. Numeral 48 designates the pencil which pushes with its unfinished point against the free end of control lever 40, as shown in Fig. 9. As soon as the control lever is moved through a certain distance by means of the pencil point, and the stop pin 37 is correspondingly raised to a certain distance, the switch operating member 45 is released to the influence of spring 49, whereby the switch operating member 45 is rotated so as to break the electrical circuit to the driving motor of the machine and thereby stop the driving of the machine. By means of the adjusting element 43 the stopping point of the machine can be regulated by adjusting the position of control lever 40. In this manner it is possible to release the means for stopping the drive of the machine at different grades of sharpness of the pencils being sharpened.

Figs. 10 and 11 show an automatic means for stopping the operation of the machine according to which a link 51 is pivotally mounted about pin 50 on gear wheel 13. Spring 52 bears against said link 51. The link 51 has a cutout portion 53 through which a pin 54 passes, the said pin 54 being fixedly connected to the plate 3. The link 51 is provided at its free end with an extension 55 having an inclined surface. Arranged within the housing 1 is a switch which has an operating lever 56 carrying at its free end a pin 57. The said pin 57 is located so that it lies within the path of movement of the extension 55 of link 51. The position of pin 57 with respect to link 51 is determined by means of the position of plate 3 with respect to gear wheel 13, and in accordance with this arrangement, the position of the elements illustrated in Fig. 10, in which the cut out portion or detent 53 of link 51 rests on pin 54, obtains when the guiding elements 19 are in their position of rest where they are drawn by the spring 23 in towards the central axis about which they are arranged. Thus, in the position of the elements shown in Fig. 10, the switch to which operating element 56 is attached will be opened by the rotation of element 16 when no pencil is in the machine and the guiding elements 19 are not spread apart from each other. In another case, if the guiding elements 19 are spread apart from each other, the link 51 is pivoted outwardly by means of pin 54 so that the extension 55 does not come in contact with the pin 57 and the shutting-off switch is not actuated.

Fig. 12 shows the driving motor 58 whose shaft 59 is connected to the driving shaft 15 for the cutting tool by means of a slip clutch. The slip clutch can be of any known construction and the pressure thereof can be adjusted in any suitable known manner.

It is advantageous to make the feeding apparatus reversible so that the machine can operate forwardly as well as rearwardly. This reversibility can be mechanically obtained by means of a changeable gear system, or the like, or it may be obtained electrically by reversing the poles of the electric motor. In this way it is possible to

sharpen pencils which are so small that they are completely fed into the machine and by reversing the direction of feeding the sharpened short pencils can be fed back out of the machine.

Fig. 12 shows a battery connected to the field of motor 58 and a switch means 58' connected to the armature of the motor 58 for reversing the polarity thereof. When switch members 58a and 58b are in the position shown in Fig. 12, the current flows in one direction through the armature, and when the arm 58b is connected to the contact 58c and arm 58a is connected to the contact 58d current will flow through the armature in a reverse direction.

As may be seen from Fig. 17, the gearing of the machine may be protected from shavings cut from the pencil by a sealing material which is made of a disc of soft rubber 65, which comprises an opening in its center through which the pencil 48 passes, and which is clamped at its outer end to a ring, for example, in the form of a circular ring 66 so that the rubber disc 65 together with the ring 66 may rotate with the pencil 48 in the housing 4. In order to effect this arrangement the ring 66 is guided by the end of sleeve 67.

The Figures 18 and 19 show another embodiment of a means for sealing off the gearing of the machine from shavings cut from the pencil. Brush hairs 69 are radially clamped within a flanged ring 68 of U-shaped cross section which extends over about 480° in such a way that the brush hairs 69 may lie with their free ends on the outer surface of the casing of pencil 48. The flanged ring 68, which, as mentioned above, extends for more than a complete circle so that both of its free ends 70 and 71 overlap with each other, as shown in Fig. 19, is mounted between the limiting pins 72 which are fastened to guiding elements 19. The flanged ring 68 is of such a size that it is yieldingly and resiliently clamped between the limiting pins 72. Thus, the flanged ring 68 with the brush hairs 69, follow the position of the limiting pins 72 on guiding elements 19 so that the free ends of the brush hairs fit themselves to the respective diameters of the various pencils to be sharpened, and the circle of brush hairs can be opened and shut in a manner similar to the opening and shutting of an iris shutter.

The following is an explanation of the operation of the machine of my present invention:

When the operating lever 31, shown in Figs. 1 and 3, is depressed, the ring shaped disc 29 is turned through a certain angle. As a result of this depression of operating lever 31 the guide lever 26, which is provided with the arm 27 located at right angles thereto, is held back by means of the spring 36 so that the clamping mechanism 25 which is fixed to the guide lever 26 can be turned with its slot and firmly grasp the ringshaped rim 24 of plate 8 in the slot which is then located in an inclined position; and in this way the rim 24 and plate 8 are carried along with the guide lever 26. In this manner the pins 9 of guiding elements 19 are moved outwardly in the guide slots 60 of plate 8 and the guide elements 19 and feeding gears 21 therewith are moved apart from each other. The clamping means for the pencil to be sharpened is thereby opened, and at this time a pencil 48 can be inserted through the conical opening 4 as shown in Fig. 2. During the rotation of ring-shaped disc 29 upon depression of operating lever 31, the guide lever 26 bears against the stop 28 so as to limit the rotation of ring shaped disc 29. In this

manner, the slot of clamping means 25, which in effect forms a pair of clamping jaws, is turned in a direction where it is again tangential to the rim 24 and the guide lever 26 is firmly held in this position of rest by means of the pawl 33. The plate 8 is thereby released and can freely rotate. In this manner the pins 9 of guiding elements 19 move towards the inner end of slot 60 under the influence of springs 23, and the gripping means 19, 20, 21 closes itself upon the pencil 48. At its lowest position of movement the operating lever 31 closes a switch (not shown) which permits current to be supplied to the motor 58.

The motor 58 now drives shaft 15 and the cutting tool 16 therewith by means of a slip clutch 59, and by means of the worm drive 14, the motor drives shaft 13 and pinion 12 connected thereto so as to rotate gear wheel 10 which carries therewith the pins 18 of clamps 19, 20, 21 so that the said clamps rotate about the pencil axis X-Y, whereby the feeding gears 21 rotate in the ways of the spiral gear 7, so that the pencil 48 which is firmly grasped in the teeth 22 of the gears 21, is constantly moved forwardly in the direction of X towards Y while constantly rotating. The pencil point locates itself in the holding element 6, as shown in Fig. 2, and is sharpened by means of a rotating cutting tool, such as, for example, the two-bladed knife 16.

After the operating lever 31 is released to the influence of spring 36 so as to again return to its original position, the right-angle portion 27 of guide lever 26 bears against stop 25 and simultaneously limits the motion of the operating lever 31. In this position of the operating lever, the pawl 33 is again brought to its rest position by the sliding of its inclined end 34 against the corresponding inclined surface of stop 35 so that it is raised out of engagement with guide lever 26. In this manner the guide lever 23 can again be pivoted upon the next actuation of operating lever 31 and in the above explained manner can again take the position where the clamps 19, 20, 21 are spread apart from each other so that the pencil with the completely sharpened point can be removed from the machine. It is also possible to remove the pencil from the machine while the machine is operating.

If it should happen that the operating lever 31 is depressed when there is no pencil in the conical opening 4 and when the clamps 19, 20, 21 are located inwardly toward the axis about which they are centrally arranged, then, as was described above, the plate 8 through the jaws of clamping means 25 is turned and with plate 8 the pin 54 is turned which is located in the detent 53 of link 51 when the clamps 19, 20, 21 are in their said inward inoperative position. In this manner, the extension 56 of link 51 moves into contact with pin 57 and operates switch operating member 56 to stop the operation of the machine. Thus when the operating lever 31 is depressed but there is no pencil in the machine the motor is shut off after having turned the gear wheel 10 less than one revolution. On the other hand, if the link 51 is moved outwardly by means of guide elements 19 as soon as a pencil is placed in the machine, the extension 56 of link 51 in this operating position passes by the pin 57 and does not actuate switch operating member 56.

In the case where a great resistance to the running of the electric motor 58 occurs because of particles of dirt in the gears or because of other disturbances, the slip clutch 59 located be-

tween electric motor 58 and drive shaft 15, as shown in Fig. 12, will slip when a certain magnitude of turning moment is obtained so that the transmission of power between the drive shaft of motor 58 and the drive shaft 15 is broken. In this way the windings of the motor cannot be damaged by a current overload, and accidents to the cutting tool and gearing produced by overloads are avoided. The pressure of the slip clutch can be regulated in any known way such as, for example, by adjusting the spring pressure of spring 61, shown in Fig. 12.

According to the invention there is provided an adjustable, automatic machine-stopping mechanism which is released by the point of the pencil being sharpened. This mechanism is illustrated in Figs. 7 to 9. As soon as pencil 48 presses inwardly with respect to holding means 3 through a certain distance, the incomplete pencil point pushes against the control lever 43 which raises stop pin 37 out of the path of movement of switch operating member 45 so as to free member 45 which then turns under the action of spring 49 and cuts off the current supply to the motor so that the machine will stop. At this time the arcuate segment 47 of switch operating member 45 raises the stop pin 37 a further distance so that the end of control lever 43 is located a few mm. in advance of the pencil point so as to move ahead of the forward motion of the pencil point. In this manner it is possible to move the pencil further so that the sharpening of the point can be completed and is unhindered by control lever 40. This completion of the sharpening of the pencil points obtained by making use of the kinetic energy of the motor armature by means of a flywheel, for example. The drive shaft 15 being connected to the motor armature is thereby turned so as to rotate the cutting tool and finish the sharpening of the pencil point. By means of adjusting lever 43 the control lever 40 can be set to any desired position for shutting off the machine, so that, for example, in the sharpening of writing or color pencils where a blunt point is desired the sharpening process can be automatically interrupted at any desired degree of sharpness of the point.

In Fig. 2 the cutting tool is shown to be a two bladed knife 13 illustrated in Figs. 13 and 14 as having inclined straight cutting edges. The knife however can obviously have any suitable construction such as that of a milling cutter, for example. Knives having a small cutting angle are easiest to manufacture and sharpen. It has been found to be especially suitable, in the operation of the machine, to rotate the cutting tool with a high speed of rotation which is somewhat more than 20,000 rotations per minute. In this manner, it is possible to obtain faultless points in pencils which are made of inexpensive wood and which preferably have soft marking materials located therein. The motor 58 need only be of a small size, and the pencil guiding and switching operating mechanisms are all compactly constructed, so that the entire machine is of a small size. The sharpening of the pencil takes only a few seconds so that the machine is not only suitable for pencil sharpening in offices but can also be used to sharpen new pencils in pencil manufacturing factories.

Instead of a cutting tool it is possible to use other shaving removing tools such as grinding wheels.

The machine has the advantage that it can sharpen all types of pencils of all usable diam-

eters. It is usable for thin pencils such as those having a diameter of 3 mm., for example, and can also be used for color pencils having a diameter of about 13 mm. In order to sharpen the last mentioned pencils of large diameter, a form of knife which comprises a convexly curved or angularly shaped cutting edge 62 or 63, as shown in Figs. 14 and 15, has proved itself to be most suitable. Particularly, the angular cutting edge 63 has proved to be very satisfactory in performance, while also being very easy to sharpen. The cutting tools above described produce on thick pencils over 7 mm. in diameter an offset pencil point such as that illustrated in Fig. 16. This has the advantage that a short but sharp and slender point 64 may be obtained in thick writing or drawing pencils such as color pencils, whereby labor and materials are saved and the pencil remains usable. By means of the same shaped knife, smaller sized pencils can also be sharpened in the same manner and with the same apparatus. It is possible to sharpen very small pencils in the machine, whereby the usability of the machine is proportionally increased. The sharpening of the smallest pencils with faultless points can be obtained with a machine constructed according to the invention, as distinguished from conventionally constructed sharpening machines. Also, the sharpening of the shortest practically usable pencils can be accomplished in the machine of my present invention so that it is not necessary to give up the use of mechanical devices in order to make a point on a short pencil.

A particular noteworthy characteristic of the invention is the combination of an automatic clamping means, which grips the pencil to be sharpened in a gripping apparatus so that the pencil is held firmly and is simultaneously rotated and fed into the machine, with a sharpening apparatus in which the cutting tool rotates at a very high speed so that the marking material which rests freely in the pencil is pressed against the pencil casing by the cutting pressure and movement of the rotating cutting tool, which is opposed to the forward motion of the pencil. In this manner the breaking or tearing of a section of the marking material of the pencil being sharpened is safely avoided.

The new machine is fully automatic and is throughout characterized by the fact that it lends itself to many different types of uses and can fill many special requirements with a particularly simple and suitable mechanism. Moreover, when the operation of the machine is for some reason faulty, the machine shuts itself off without any accidents or disadvantage. Instead of the described driving means, other driving elements may obviously be used to produce the same results produced by the described operation of the machine. In place of guiding elements 19 which are provided with gears by which the pencil is held and moved forwardly by the turning thereof, another means for gripping the pencil can be provided which itself simultaneously turns and moves axially so as to carry the pencil along therewith. In like manner the other described driving elements can be differently constructed by the use of suitably working parts without in any way changing the fundamental principle of the invention.

It will therefore be understood that each of the elements described above or two or more together, may also find useful application in types

of sharpening machines other than that described above.

While I have illustrated and described the invention as embodied in a machine for sharpening pencils, I do not intend to be limited to the details shown since various modifications and structural changes may be made without departing from the spirit of my invention.

Without further analysis the foregoing will so fully reveal the gist of my invention that others can by applying current knowledge readily adapt it for various applications without omitting features, that, from the standpoint of the prior art, fairly constitute the essential characteristics of the generic or specific aspects of this invention, and, therefore, such adaptations should and are intended to be comprehended within the meaning and range of equivalents of the following claims.

What I claim as new and desire to secure by Letters Patent is:

1. A pencil sharpener, comprising, in combination, support means for supporting a pencil to be sharpened; rotatably mounted cutting means located adjacent said support means for cutting a pencil; turnable gripping means mounted on said support means for gripping a pencil to be sharpened and, upon turning, feeding the pencil to said cutting means to be cut thereby; and a single drive means operatively connected to said cutting means and said gripping means for simultaneously operating said cutting means and turning said gripping means to automatically feed a pencil to be sharpened to said cutting means, whereby the pencil to be sharpened may be automatically fed and cut.

2. A pencil sharpener, comprising in combination, support means for supporting a pencil to be sharpened; gripping and feeding means mounted on said support means for gripping and feeding and rotating a pencil to be sharpened; rotatably mounted cutting means located adjacent said support means for cutting a pencil fed by said gripping and feeding means; and a single drive means operatively connected to said gripping and feeding means and said cutting means for simultaneously operating said gripping and feeding means and said cutting means, whereby the pencil to be sharpened may be automatically fed and cut.

3. A pencil sharpener, comprising in combination, support means for supporting a pencil to be sharpened, said support means being located about a central axis; gripping and feeding means for feeding a pencil to be sharpened along said central axis, said gripping and feeding means being mounted on said support means for rotation about said central axis; rotatably mounted cutting means located adjacent said central axis for cutting a pencil to be sharpened; and a single drive means operatively connected to said cutting means and said gripping and feeding means for operating said cutting means and gripping and feeding means and for rotating the latter about said central axis so as to thereby rotate a pencil to be cut simultaneously with the sharpening of the same.

4. In a pencil sharpener, in combination, support means for supporting a pencil to be sharpened, said support means being located about a central axis; gripping and feeding means for feeding a pencil to be sharpened along said central axis, said gripping and feeding means being mounted on said support means for rotation about said central axis and said gripping and feeding means comprising a plurality of plate

members mounted for movement toward and away from said central axis, resilient means operatively connected to said plate members for urging the same towards said central axis, and a

5 plurality of gripping gears respectively mounted on said plate members for rotation about axes normal to said central axis; rotatably mounted cutting means located adjacent said central axis for cutting a pencil to be sharpened; and a single drive means operatively connected to said cutting means and said gripping and feeding means for operating said cutting means and gripping and feeding means and for rotating the latter about said central axis so as to thereby rotate a pencil to be cut simultaneously with the sharpening of the same.

6. In a pencil sharpener, in combination, at least two plate members symmetrically located about a central axis, said plate members being

20 mounted for movement toward and away from said central axis and being located in a plane normal to said central axis; resilient means operatively connected to said plate members for urging the same toward said central axis; at least

25 two gripping gears respectively mounted on said plate members for rotation about axes normal to said central axis and parallel to said plane, said gripping gears being adapted to engage a pencil located along said central axis when said plate

30 members are urged towards said central axis by said resilient means; and reversible drive means operatively connected to said gears for rotating the same in opposite directions, whereby, when said gears are rotated in one direction by said

35 reversible drive means, a pencil may be automatically fed to be sharpened and, when said gears are rotated in a direction opposite to said one direction by said reversible drive means, an already sharpened pencil may be automatically

40 removed from the sharpener.

6. In a pencil sharpener, in combination, at least two plate members symmetrically located about a central axis, said plate members being mounted for movement toward and away from said central axis and being located in a first plane normal to said central axis; resilient means operatively connected to said plate members for urging the same toward said central axis; at least

45 two gripping gears respectively mounted on said plate members for rotation about axes normal to said central axis and parallel to said plane, said gripping gears being adapted to engage a pencil located along said central axis when said plate

50 members are urged towards said central axis by said resilient means; and reversible drive means operatively connected to said gears for rotating the same in opposite directions, whereby, when said gears are rotated in one direction by said

55 reversible drive means, a pencil may be automatically fed to be sharpened and, when said gears are rotated in a direction opposite to said one direction by said reversible drive means, an already sharpened pencil may be automatically removed from the sharpener, said reversible drive

60 means comprising a spiral gear located in a second plane substantially parallel to said first plane and meshing with said gripping gears and transmission means interconnecting said gripping gears and spiral gear for turning movement with respect to each other about said central axis.

7. In a pencil sharpener, in combination, a stationary spiral gear formed with a central aperture passing therethrough and located along a central axis, the gear teeth of said spiral gear being located in a first plane normal to said cen-

11

tral axis; support means located in a second plane parallel to said first plane and being mounted for rotation about said central axis; at least two gripping gears symmetrically located about said central axis and meshing with said spiral gear, said gripping gears being mounted on said support means for movement toward and away from said central axis and for rotation about axes normal to said central axis and parallel to said first plane; resilient means operatively connected to said gripping gears for urging the same towards said central axis; and drive means operatively connected to said support means for rotating the same about said central axis so as to thereby cause said gripping gears meshing with said spiral gear to rotate and feed a pencil gripped therebetween along said central axis.

3. In a pencil sharpener, in combination, a stationary spiral gear formed with a central aperture passing therethrough and located along a central axis, the gear teeth of said spiral gear being located in a first plane normal to said central axis; support means located in a second plane parallel to said first plane and being mounted for rotation about said central axis; at least two gripping gears symmetrically located about said central axis and meshing with said spiral gear, said gripping gears being mounted on said support means for movement toward and away from said central axis and for rotation about axes normal to said central axis and parallel to said first plane; resilient means operatively connected to said gripping gears for urging the same towards said central axis; and reversible drive means operatively connected to said support means for rotating the same about said central axis so as to thereby cause said gripping gears meshing with said spiral gear to rotate and feed a pencil gripped therebetween along said central axis when said drive means rotates said support means in one direction about said central axis, and so as to cause said gripping gears to move an already sharpened pencil out of the sharpener when said drive means rotate said support means in a direction opposite to said one direction.

9. In a pencil sharpener, in combination, a stationary spiral gear formed with a central aperture passing therethrough and located along a central axis, the gear teeth of said spiral gear being located in a first plane normal to said central axis; support means located in a second plane parallel to said first plane and being mounted for rotation about said central axis; at least two gripping gears symmetrically located about said central axis and meshing with said spiral gear, said gripping gears being mounted on said support means for movement toward and away from said central axis and for rotation about axes normal to said central axis and parallel to said first plane; resilient means operatively connected to said gripping gears for urging the same towards said central axis; drive means operatively connected to said support means for rotating the same about said central axis so as to thereby cause said gripping gears meshing with said spiral gear to rotate and feed a pencil gripped therebetween along said central axis, said drive means comprising an elongated drive shaft and worm gear means interconnecting said drive shaft

12

and support means for rotating the latter at a lesser rate of speed than that at which said drive shaft rotates; and blade means mounted on said drive shaft for cutting a pencil fed by said gripping gears.

10. In a pencil sharpener, in combination, a stationary spiral gear formed with a central aperture passing therethrough and located along a central axis, the gear teeth of said spiral gear being located in a first plane normal to said central axis; support means located in a second plane parallel to said first plane and being mounted for rotation about said central axis; at least two gripping gears symmetrically located about said central axis and meshing with said spiral gear, said gripping gears being mounted on said support means for movement toward and away from said central axis and for rotation about axes normal to said central axis and parallel to said first plane; resilient means operatively connected to said gripping gears for urging the same towards said central axis; drive means operatively connected to said support means for rotating the same about said central axis so as to thereby cause said gripping gears meshing with said spiral gear to rotate and feed a pencil gripped therebetween along said central axis, said drive means comprising a motor and an elongated drive shaft driven thereby and worm gear means interconnecting said drive shaft and support means for rotating the latter at a lesser rate of speed than that at which said drive shaft rotates; blade means mounted on said drive shaft for cutting a pencil fed by said gripping gears; and slip clutch means mounted between said motor and drive shaft for preventing operation of the pencil sharpener under overload conditions.

11. A pencil sharpener as defined in claim 3 and wherein said support means comprises a stationary plate formed with an aperture located about said central axis and adapted to have a pencil to be sharpened extending therethrough, said plate having an annular projection fixed thereto; and a guiding ring mounted on said annular projection for rotation thereabout and being connected to said gripping and feeding means to support the same for rotation about said central axis.

12. A pencil sharpener as defined in claim 7, and wherein said gripping gears have teeth each of which is pointed and provided on one side with a curvature corresponding to the shape of the groove in the spiral gear.

ALFRED GUHL.
